UNITED STATES PATENT OFFICE

VLADIMIR M. ZAIKOWSKY, OF PASADENA, CALIFORNIA, ASSIGNOR TO STANDARD OIL DEVELOPMENT COMPANY, OF NEW YORK, N. Y., A CORPORATION OF DELAWARE

INTERNAL-COMBUSTION ENGINE

Application filed March 8, 1929. Serial No. 345,477.

This invention relates to improvements in internal combustion engines, and more especially to an improved valve mechanism for such engines.

One of the features of my invention is the provision of improved valve mechanism that is simple to construct, easy to assemble, and efficient in operation.

My improved valve mechanism is also adapted to be used in connection with any cycle or method of operation of an internal combustion engine.

Other features and advantages of my invention will appear more fully as I proceed with my specification.

In that form of device embodying the features of my invention shown in the accompanying drawings; Figure 1 is a view partly in side elevation and partly in vertical section; Fig. 2 is a view taken as indicated by line 2 of Fig. 1; Fig. 3 is a fragmentary vertical sectional view, as indicated by the line 3 of Fig. 2; Fig. 4 is a view taken as indicated by the line 4 of Fig. 1; Fig. 5 is a diagrammatic view showing the circulation of the gases from the cylinder through the cooling chamber and back to the cylinder; and Figs. 6 to 13, inclusive, are diagrammatic views showing the sequence of operations of the valve in one cylinder.

As shown in the drawings, the invention is illustrated as embodied in an internal combustion engine of the four cylinder, four-cycle type, although it is obvious that the invention may be used in connection with engines of different types.

I have here shown the invention also as incorporated in an engine using a supercharger; but it is obvious that the invention is equally applicable for use in connection with an engine not using such a supercharger. For the purpose of illustration, I have also described here a certain method of operating the engine; although it is obvious that the invention, in its broadest aspects, can be utilized in connection with other methods of operating internal combustion engines.

As shown in the drawings, the engine has the usual crank case 10, crank shaft 11, cranks

12, connecting rods 13, and pistons 14 operating in the cylinders 15.

Suitable water chambers around the cylinders and heads thereof may be supplied, as indicated by 16, for the purpose of cooling. 55 Numeral 17 indicates the usual spark-plugs.

A detailed description of the construction and operation of one cylinder, and its corresponding parts, will be sufficient, as it is to be understood that the other cylinders operate in a similar manner in any desired firing order.

The head of the cylinder is provided with a quadrilateral port, indicated by O. Above the cylinder heads are arranged two plates 65 P, P, each adapted for bodily circular sliding movement in its own plane. Each plate is provided with quadrilateral ports C, similar in shape to the ports O in the cylinder head. There is one plate for each end pair 70 of cylinders.

There are also provided suitable exhaust and inlet manifolds (not shown) to which the exhaust pipes 18 and inlet pipes 19, respectively, are connected. It is to be understood 75 that a suitable carburetor (not shown) or other means is provided for admitting a combustible mixture into the inlet pipes, in a well known manner.

In general, the cylinder block below the 80 plate P is indicated by 20, and the cylinder block head above the plate P is indicated by 21. The plane surfaces of the top of the cylinder block, as indicated by 20, and the bottom of the block head, as indicated by 21, 85 that is, the plane surfaces on both sides of the plate P are well fitted and lubricated so that gas from the cylinders cannot escape between contacting surfaces.

The exhaust and intake pipes 18 and 19 connect with similar pipes 18^a and 19^a, preferably cast in the cylinder block and head, and these passages have terminals or outlet ports near the cylinder ports O. I prefer to provide two such intake passages for each cylinder, one below and one above the plate P. The terminals or outlet ports are indicated by E and I, indicating, respectively, exhaust and inlet. For each cylinder, the two inlet ports referred to are arranged one di- 130

rectly above the other. Reference to Fig. 1 will show quite clearly, in sectional view, one exhaust port E at the end of the exhaust passage 18^a and two inlet port I, I, one above and one below the plate P. It is to be understood that all the exhaust and inlet ports are arranged in the same manner, and reference to Fig. 2 will show quite clearly the placing of such ports. It is to be noted that each of these ports is in the shape of a long narrow slot.

Means are provided for imparting to each plate P a rotary circular motion in its own plane at one-half the speed of the crank-shaft. This is accomplished by providing the counter-shaft 22 driven from the crank-shaft 11 by the silent chain 23. The shaft 22 is provided with two worms 24, each driving a gear 25 on the lower end of a shaft 26 which carries at its upper end a crank wheel 27 with a crank pin A in the plate P. It is to be understood that there are two such driving mechanisms, one on each end of the engine (see Fig. 2) so that the plates P are given a bodily rotary circular motion in their own plane by the crank pins A, A.

The plates are rotated in opposite directions but so timed that the adjacent edges P', P' are always close together. The crank wheel 27 for each plate is at the corner, and the two adjacent corners of each plate are provided with similar wheels 27' driven by the plates through the pins A'. Each of the wheels 27' has a portion of its periphery counterweighted, as indicated by 27'', such counterweights serving to counter-balance the weight of the plates. By providing the wheels 27' at the diagonally opposite corners of each plate, the plate is given a bodily circular movement by the driving crank wheel 27 and prevented from twisting.

I shall now describe the operation of the engine without considering, for the moment, the supercharging. The pins A, A move each plate P so that the ports C will overlap the cylinder port O and the exhaust port E for the exhaust, and overlap the cylinder port O and the inlet ports I for the inlets. It is to be understood that the various ports may be so shaped and spaced and the extent of movement of the plates P so varied, and their rate of movement so timed, as to give the desired times for opening and closing the exhaust and inlet ports. In other words, the engine may be timed as desired. As here shown, the ports are so arranged as to give substantially the usual timing of a four-cycle engine. As shown in Fig. 2, cylinder No. 1 from the left is at the lower dead center and ready to start the exhaust stroke. It will be seen that the exhaust valve has already partly opened, permitting some of the exhaust to escape. Cylinder No. 2 has its piston at the top dead center, the compression stroke has just been completed and the expansion stroke is just ready to start. It

will be seen that plate D is moving, as indicated by the arrows, and that both the inlet and exhaust ports are closed. Cylinder No. 3 has its piston at the top dead center and is ready to start the intake stroke. It will be seen that the inlet is partly open and the exhaust almost closed. Cylinder No. 4 has its piston at the bottom dead center ready to start the compression stroke. It will be seen that the exhaust valve is closed and the inlet is just about closed.

I shall now describe the supercharging in connection with my engine. In general, this comprises the provision of an auxiliary cooling chamber with means for opening communication between the cylinder and the cooling chamber during the latter part of the expansion stroke of the engine to force burned gases into the chamber and means for again opening communication between the cylinder and the cooling chamber during the compression stroke to permit the cooled gases to re-enter the cylinder from the chamber in order to supercharge the cylinder. The cooling chamber is preferably made more or less in tubular form and two ports provided for each cylinder, one for the gases to leave the cylinder and pass into the cooling chamber and the other to re-admit the cooled gases into the cylinder from the cooling chamber.

Means are also provided to cause the gases to circulate through the cooling chamber so that they will become sufficiently cooled. The opening and closing of the ports above referred to is also accomplished by means of the plate P, and this will now be described more in detail.

The cylinder block is provided with a port Es for each cylinder, the pair at each end connecting with a pipe 30 leading to a suitable cooling chamber 100. The cylinder head is likewise provided with a port Is for each cylinder, the pair of said ports at each end connecting with the pipe 31 that leads from the cooling chamber 100. The cooling chamber includes a pipe coil R adapted to be cooled by water surrounding the same. For example, water may be introduced at 101 and permitted to escape at 102. For example, water may be introduced into the opening 101 by the regular water pump (not shown) of a motor vehicle, such pump obtaining the water from the radiator. After leaving the cooling chamber through the opening 102, the water may be introduced into the water spaces of the cylinder block and head in the usual manner for cooling the same. The direction of flow of gases into and out of the cooling chamber is indicated by the arrows in Fig. 5. The pipe 30 receives the hot gases from the cylinders and the pipe 31 delivers them back in cooled condition to the cylinders. For convenience, the port Es and co-operating parts which receive the hot gases from the cylinders may be referred to as the hot valve and the port Is and

co-operating parts which return the cooled gases to the cylinders may be referred to as the cold valve.

The ports E_s and I_s are controlled in the following manner. The plate P is provided with two slanting openings or ports E_m and I_m for each cylinder. Their function is to transfer part of the burned gases from the cylinder into the cooling chamber at the end 10 of the expansion stroke and to reintroduce cooled exhaust gases from the chamber into the cylinder during the compression stroke. The hot gas is conducted to the cooling chamber by the port E_m in the plate moving into 15 registry with the port E_s in the block and the upper end of the cylinder, as indicated by O' (see Fig. 3), the port C in the plate permitting communication between O and O' . The cooled gas is reintroduced through the simultaneous overlap of the opening O and the port 20 I_s by the port I_m in the plate. The sequence of operations for one cylinder in this respect is shown in Figs. 6 to 13, inclusive.

The port E_m works in conjunction with the 25 port E_s in the block to permit gases to escape from the cylinder into the cooling chamber and the port I_m works in conjunction with the port I_s in the head to reintroduce cooled gases back into the cylinder.

The exact timing of the valves, and their size and spacing may be arranged as desired in order to give any desired cycle or method of operation. Purely by way of example, I have here shown one possible timing. For 30 example, in Figs. 6 to 13, inclusive, I have shown a possible timing for cylinder No. 1. For example, the hot valve or valve E_m may commence opening about 80° before lower dead center and completely close about 40° before lower dead center on the expansion 35 stroke, and the regular exhaust valve may begin to open about when the hot valve is at its maximum opening. The cold valve or valve I_s may begin to open from 25 to 30° past lower dead center and completely close from 95 to 105° past lower dead center on the compression stroke. Figs. 6 and 7 may indicate the crank about 50° before lower dead center on the expansion stroke. It will be seen 40 that the hot valve or valve E_m is at its maximum opening and the regular exhaust valve is just commencing to open. Figs. 8 and 9 may indicate the crank just before the top dead center at the end of the exhaust stroke and just before starting the intake stroke. Both the valve I_m and E_m , that is, the cold 45 valve and hot valve, respectively, are closed, the exhaust valve is just about to close, and the inlet valve is just about to open. Figs. 10 and 11 may indicate the crank about 30° past lower dead center on the compression stroke. The regular inlet valve has closed and the cold valve or I_m is beginning to open. This cold valve may close at about 95 to 105° past 50 lower dead center, but this position is not

shown in the drawings. Figs 12 and 13 may indicate the crank just before the top dead center at the end of the compression stroke and before the expansion stroke. The regular exhaust and inlet valves are closed and both the hot and cold valve, that is, the ports E_s and I_s , are also closed.

In general, it may be stated that the port E_s , or hot valve, is open at the end of the expansion stroke. It should open just before 55 the regular exhaust valve begins to open. Hot gas will, therefore, flow from the cylinder into the cooling chamber. As soon as the regular exhaust valve opens, the pressure in the cylinder will drop rapidly; but the valves are so timed that before the pressure in the cylinder drops below the pressure in the cooling chamber that is desired, the port E_s , or hot valve, is closed, thus preventing back flow of gases from the cooling chamber 60 through the port E_s into the cylinder.

In general, it may be stated that the cold valve or port I_m that permits gases to flow back into the cylinder from the cooling chamber opens some time during the compression stroke. The exact timing of these valves may be made as desired. For example, as stated, they may begin to open from 25 to 30° past lower dead center and completely close at from 95 to 105° past lower dead 65 center on the compression stroke. In general, the timing should be so that during the compression stroke some cool gases will flow from the cooling chamber back into the cylinder, thus assisting in cooling the charge. In general, it may be stated that the cold valve should remain open long enough for the pressure to become about equalized between the cylinder and the cooling chamber and then close.

The result of the operation above described is to give a great increase in the pressure of the charge in the cylinder during the last part of the compression stroke and throughout the working stroke, so that the engine will 70 operate at a greater efficiency. Owing to this cooling and supercharging, detonation is prevented or retarded.

Each cylinder, in turn, communicates with the cooling chamber during the latter part of its working stroke to deliver hot burned gases to the cooling chamber and receive from the cooling chamber a cooled charge of burned gases during the compression stroke. This is a very simple and efficient means for supercharging the engine by means of the exhaust gases to lessen or prevent the detonation which might otherwise occur and to increase the efficiency of the engine.

While I have shown and described certain embodiments of my invention, it is to be understood that it is capable of many modifications. Changes, therefore, in the construction and arrangement may be made without departing from the spirit and scope of the 125

invention as disclosed in the appended claims, in which it is my intention to claim all novelty inherent in my invention as broadly as possible, in view of the prior art.

What I regard as new, and desire to secure by Letters Patent, is:

1. An internal combustion engine including; a cylinder with a single port in or near the head; a piston in the cylinder; a movable plate lying over the cylinder port and having a port therein; exhaust and inlet passages having ports near the cylinder port; and means for moving the plate to cause it to overlap the cylinder port and the exhaust or inlet ports with its port in accordance with the desired cycle.
2. An internal combustion engine as claimed in claim 1, in which the exhaust or inlet passages have ports above and below the plate.
3. An internal combustion engine as claimed in claim 1, having four cylinders in line, with two plates, one for the pair of cylinders at each end, and means for imparting bodily circular movement to said plates, each in its own plane, in opposite directions, the adjacent edges of said plates being substantially the same distance apart during the complete rotary movement of said plates.
4. An internal combustion engine including; a cylinder with a single port in or near the head; a piston in the cylinder; a movable plate lying over the cylinder port and having a port therein; exhaust and inlet passages having ports near the cylinder port; and means for moving the plate in a circular path to cause it to overlap the cylinder port and the exhaust or inlet ports with its port in accordance with the desired cycle, said overlapping ports having relatively long sides substantially tangential to the circular movement of the plate at the point of maximum opening of said ports.

In witness whereof, I have hereunto set my hand this 22nd day of January, 1929.

WLADIMIR M. ZAIKOWSKY.
